UNITED STATES PATENT OFFICE.

ULRIC WEGMAN, OF ITHACA, NEW YORK.

DESIGN FOR A HEADLIGHT-LENS.

58,845.

Specification for Design.

Patented Aug. 30, 1921.

Application filed June 4, 1920. Serial No. 386,605. Term of patent 3½ years.

To all whom it may concern:

Be it known that I, ULRIC WEGMAN, a citizen of the United States of America, residing at Ithaca, in the county of Tompkins and State of New York, have invented a new, original, and ornamental Design for a Headlight-Lens, of which the following is a specification, reference being had to the accompanying drawing, forming part thereof.

The figure is a view in front elevation of a headlight lens, showing my new design.

I claim:

The ornamental design for a headlight lens, as shown.

ULRIC WEGMAN.
